UNITED STATES PATENT OFFICE.

CHARLES J. VAN DEPOELE, OF LYNN, MASSACHUSETTS.

SYSTEM OF SUPPLYING CURRENTS TO ELECTRIC RAILWAY SYSTEMS.

SPECIFICATION forming part of Letters Patent No. 417,122, dated December 10, 1889.

Application filed April 13, 1889. Serial No. 307,131. (No model.)

To all whom it may concern:

Be it known that I, CHARLES J. VAN DEPOELE, a citizen of the United States, residing at Lynn, in the county of Essex and State of Massachusetts, have invented certain new and useful Improvements in the System of Supplying Currents to Electric Railway Systems, of which the following is a description, reference being had to the accompanying drawings, and to the letters and figures of reference marked thereon.

My invention relates to improvements in systems of supplying current to the working-conductors of electric railways. In many instances the location of the source of current is necessarily so remote from outlying portions of the line that there is considerable drop of potential in transmitting the supply-current from the generator to the working-conductors. A system of auxiliary conductors or feeders extending throughout the entire length of the line and parallel with the working-conductors has been used to convey the supply-current thereto. This system, however, possesses the disadvantage of requiring feeding-conductors of the same length as the working-conductors and in many instances larger in cross-section—in other words, a complete double system of conductors. No parallel feeding-conductors are employed by me, the current being supplied to the working conductor or conductors direct from the generating-station, and the said working-conductors are themselves of sufficient conductive capacity to carry the current between connections without material loss.

My improved system comprises a bare working conductor or conductors running parallel to the line of the railway and adapted to supply current to traveling motors, between which and the said working-conductors a moving connection is established in any desirable manner. The said working-conductors may be suspended above the track or placed in sub-surface conduits, as desired. The supply-current is led from the generator through a trunk line, following the most direct route, and terminating at a point from which a number of short feeders are connected to the respective sections of the working conductor or conductors; and the respective cir-

cuits will be hereinafter referred to as the trunk-line, feeders, and the working-conductors. According to my present invention the 55 working-conductors are divided into insulated sections, whereby an accident to the conductors of any portion of the line would be localized and the remaining sections left in working condition. Where a line of railway is many miles in length, the supply-current would naturally suffer a loss of potential when transported to the most distant point. As it is desirable that the actual current supplied to the motors be of the same 65 potential throughout, the main supply-current is sent from the generator to the trunk-line and its several branches or feeder-circuits at a potential somewhat above that desired in the working-conductors, and I introduce between the said feeder and working-conductors or those relatively short and near to the generating-station an adjustable resistance, by means of which the voltage of the current flowing into the several working- 70 circuits is equalized. The adjustable resistances may be manual or automatic, as will appear, and in addition thereto I provide an automatic cut-out and signal, so that in case of a short circuit on any section further damage will be prevented and a visual signal displayed to give notice of the occurrence.

The various details of the system will be hereinafter described, and referred to in the appended claims.

Figure 1 is a diagrammatic view illustrating an arrangement of trunk and feeder circuits and a railway system embodying the invention. Fig. 2 is a diagrammatic view similar to Fig. 1 and differing therefrom 90 mainly in the disposition of the respective circuits. Fig. 3 is an enlarged detail of the current-controlling devices. (Seen in Figs. 1 and 2.) Fig. 4 is an enlarged detail view showing an automatically-operated resistance 95 between the feeder and working circuits and showing also the relative arrangement of current-controlling devices. Fig. 5 is also a detail diagrammatic view differing from Fig. 4 chiefly in the form of automatic resistance 100 employed. Fig. 6 also shows automatic means for controlling the flow of current from the feeder-circuit to the working-conductor, but differing somewhat in construction from that

seen in Figs. 4 and 5. Fig. 7 is an elevation on an enlarged scale showing means for uniting and insulating the extremities of the conductors of adjoining sections. Fig. 8 is an 5 enlarged detail of the fuse-box and signal.

As indicated in Fig. 1, A is the bare working-conductor, which is divided into nine sections, numbered from one to nine, and is shown as curved to follow the possible route 10 of a street-railway, the number of sections and curves shown being, however, merely by way of illustration.

The positive or main-supply conductors are all indicated in full lines, and for convenience 15 of illustration the return-conductor and its connections in broken or dotted lines.

In the present instance the generating-station B is located at a point remote from portions of the line and the currents are distributed to the several sections of the working-conductors by a trunk-conductor C, from which extend feeders a' a^2 a^3 a^4 a^5 a^6 a^7 a^8 a^9 , each feeder being connected to one of the sections of the working-conductors. The 20 trunk-conductor C should be of greater size than the feeders extending therefrom and its capacity must be in proportion to the number of feeders and its own length. Furthermore, it is desirable, though not essential, 25 that the feeders should connect with their sections somewhere near the central portion thereof, in order to minimize the loss of current in traversing said working-conductors. A main return trunk-conductor D' is also 30 provided, as seen in dotted lines, and the return-conductor is connected to the other side of the circuit of the working-conductors of each section by branch conductors d' d^2 d^3 d^4 d^5 d^6 d^7 d^8 d^9 .

40 In order to properly regulate and control the supply of current to the main working-conductors, it is desirable that each feeder should be connected to only a single section in order that the flow of current to the several sections may be controllable in case of 45 a short circuit on any section, or in case of damage to any portion of the working-conductors. The return trunk-conductor D' may, however, be connected to the return working-conductors by cross-connections between sections or otherwise, as most convenient, it being desirable that this conductor should connect in every direction and at any point that will reduce the resistance of the return-circuit to the lowest possible point. The return 55 working-conductor may consist of the rails of the track, the said rails being electrically connected at their ends and also connected to the return-conductor D' by the cross-connections 60 or return-feeders d' d^2 d^3 d^4 d^5 d^6 d^7 d^8 d^9 , as indicated, although more of the return-feeders may be employed, if desired.

65 The extremities of the several sections of main working-conductor are electrically disconnected, but mechanically united to form a continuous working-line by sections of insulation E, as seen on an enlarged scale in Fig.

7, where E represents a link or strip of strong insulating material—as, for instance, wood or vulcanized fiber—which should be properly 70 filled or coated with a good insulating material to render the same impervious to moisture. To each end of the link E is secured a tapering metallic ear e, which is formed with a groove e' upon its under side to receive the 75 conductor A. The said ear e is formed with a vertical aperture e^2 near its wider end and adjacent to its point of attachment to the insulator E, and the conductor is attached by passing its extremity up through the aperture 80 e^2 , when it is bent over to form a short kink and then cut off. The portion of the conductor in the groove e' of the ear e is then desirably united thereto by soldering, brazing, or welding to form a permanent attachment. The lower edge of the insulator E should be in line with and extend between the 85 apertures e^2 in the ears e, so as to constitute an uninterrupted path for the contact device.

In Fig. 1 the generating-station is indicated 90 as being at a distance from the line of railway and consequently quite remote from its outlying portions. With such a disposition of the apparatus and circuits the size and cost of trunk and feeder connections of sufficient 95 conductivity to carry the main supply-current to all sections of the working-conductor and deliver the same at a standard potential would in many instances be greater than necessary.

100 In order to reduce the size and cost of conductors, I find it convenient in many instances to generate current a few volts in excess of the desired pressure and to place a resistance in circuit with each feeder, so that the potential of the current supplied to any section may be permanently adjusted and corrected and the current in the working-conductors be of uniform potential throughout. For example, the current delivered through feeder a^5 to section 5 will have to travel considerably farther than through feeder a' to section 1. If, therefore, I provide an adjustable resistance G in the feeder-circuit a' , the potential of the current flowing into the working-conductor in 115 said section can be adjusted to be equal in potential to that flowing through feeder a^5 and into section 5 without the use of artificial resistance in feeder-circuit a^5 , and this plan I propose to employ in practice, although it 120 will be manifestly convenient to have the adjustable resistances, as seen in the drawings, in all or nearly all the circuits as a desirable means of adjusting the potential in case the 125 trunk and feeder-conductors were not of the correct proportions in the first instance.

In Fig. 2 the circuits and connections are similar to those already described, except that for illustration a system is indicated in which the generating-station is located in about a 130 central position with respect to the line of the railway. Such an arrangement of circuits is of course desirable wherever practicable, since the size and cost of the distributing-

conductors are materially lessened thereby. In said Fig. 2 is seen an organization of lines and circuits in which the central generating-station is located in a position substantially equidistant from the several sections to be supplied therefrom. When such is the case, the artificial resistances $G' G^2 G^3 G^4 G^5 G^6$ for adjusting the potential of the main supply-current may be omitted or only used on a few of the shorter feeding-circuits, or provided in all circuits or switched out on the longer circuits, as indicated by the positions of the switch-levers g , for by generating current of an initial potential of a very few volts above that desired in the working-conductors the loss in transmission can be arranged to be such as will secure the delivery of current to the working-conductors at the standard potential.

In order to prevent the flow of extraordinary current through any of the feeders, a fuse-box F is connected between each feeder and its section of the working-conductor. The said fuse-boxes also include a visual signal, which will become visible whenever the fuse is blown by the occurrence of any trouble—such as a short circuit on any section—and thus give notice of the fact.

In Fig. 3 the resistance by which the potential of the current supplied to the working-conductors may be adjusted, together with the fuse-box in circuit therewith, are shown on an enlarged scale. The fuse-box is shown in detail in Fig. 8. The fuse-box F includes a fusible strip f , normally in circuit between the binding-posts $f' f''$. A manual switch f^3 is also provided for opening the main circuit around the supports of the fusible strip for convenience in replacing a blown fuse. A pivoted visual signal F' is also provided, said signal being normally suspended within the box F by a piece of small wire f^4 , which is attached or connected to the fuse f , so that when the fuse is blown by the passage of an ordinary current the wire f^4 will be destroyed or liberated and the signal F' allowed to drop downward out of the box into sight. The potential-adjusting resistances and the fuse-boxes which are included in the several feeder-circuits are in the nature of permanent appliances, and the fuse-box is only intended to be brought into action under extraordinary circumstances, such conditions, in fact, as would otherwise produce serious damage. Means for regulating the amount of current flowing to any one section are provided in order that the other sections of the system be not deprived of the current necessary to operate the motors traveling the along. For this purpose I provide an automatic resistance device between each feeder and its working-conductor. Automatic current-regulators of many different types may be employed, some of which are illustrated in Figs. 4, 5, and 6.

In Fig. 4 is seen an automatic resistance H , in circuit with a solenoid h , connected to the

working-conductor A by the conductor h' . A movable contact I is arranged to engage the terminals of resistance H , and is in electrical connection with the feeder a' through conductor i . The contact I may be mounted upon the axis of a drum or band-wheel i' , around which passes a cord or other suitable connection I' , which is provided with a counter weight or spring at one end and connected at its other end to the core I^2 of the solenoid h . When the core I^2 is in its lowest position, the contact I is in position to short-circuit the resistance H . When, therefore, an abnormal current is flowing through the conductor i , solenoid h , and conductor h' , to the working-conductor A , the solenoid h will raise the core I^2 in proportion to the strength of the current, and as the core i^2 is lifted the band I' will rotate the drum i' and move the contact in the direction of the arrow, thereby introducing more of the coils of the resistance H into the circuit to oppose the flow of current.

The working-circuit of a motor-car is indicated in Fig. 4 by a traveling contact J , engaging the working-conductor A , the said working-circuit extending from the contact J to a fuse-box F and rheostat H' and a motor H^2 , the other terminal of which is connected to the return-conductor D . A second working-circuit between the said conductors A and D is indicated by the line D^2 , it being understood, of course, that any desired number of translating-circuits are to be connected between the said main and return conductors A and D .

In Fig. 5 a translating device, such as indicated in Fig. 4, is shown; but in this figure a somewhat different form of automatic current-regulator is seen between the feeder and working-conductors, the said current-regulator comprising two separable contacts, desirably of carbon, which upon the flow of an abnormal current will be separated, thereby introducing the resistance of an arc of greater or less length, according to the strength of the current, and said arc will be maintained until the extraordinary demand for current ceases, when the carbons will again come together and complete the circuit. The conductor i is secured to one of the carbons j , a second carbon j' , normally in contact with the carbon j , being secured to the plunger I^2 of solenoid h , which is in circuit by conductor h' with the working-conductor A . A conductor i' connects the carbon j' with the lower terminal of the solenoid h . Other means for automatically regulating the current between the said feeder and working circuits may be employed—as, for instance, as seen in Fig. 6, where an electro-dynamo motor K is arranged to operate a rheostat H . The feeder a' is connected by conductor k with one extremity of the resistance H . A rotatably-mounted traveling contact k' is arranged to engage the terminals of the said resistance

II, and is itself in electrical connection with the working-conductor A to complete the feeder-circuit through conductor L.

The motor K is, as here indicated, a series machine, although other forms of winding and connections might be employed. The said motor K is connected in multiple arc between the main and return conductors of the working-circuit. One terminal of the motor is in circuit with the working-conductor A through conductor l, and the other terminal of the motor is connected by conductor " with a solenoid M, which is connected to the return-conductor D by conductor l'. The commutator-brushes m m' are secured or connected to an actuating-lever O, which is provided at one extremity with an adjustable tension-spring Q, and at its opposite end is connected to the iron plunger q of the solenoid M.

20 A band-pulley or other suitable device R is secured upon the armature-shaft of the motor K and is connected by a belt r with a similar pulley r' upon the axis of the movable contact k'. The motor-circuit may also be provided with an indicator s, by which the current upon the line will at all times be shown. With this or an equivalent arrangement upon the presence of an abnormal current in the line-conductor A the solenoid M 30 will draw in its core q, shifting the commutator-brushes in the direction to cause rotation of the armature of the motor and movement of the contact k' in the direction of the arrow, thus switching in more of the coils of the resistance II. As the current drops in the main conductor the motor will cease to operate, the solenoid M will become weakened, and the retracting-spring Q will return the parts to a position of equilibrium which 40 is that here shown.

As indicated, current will at all times be passing through the motor-circuit, but the tension of the spring Q should be adjusted so as to overbalance the power of the solenoid M until the flow of current through the motor-circuit becomes such as to require the introduction of an additional resistance in the feeder-circuit when the power of the solenoid will be sufficient to overcome the spring Q and set the armature in motion.

Having described my invention, what I claim, and desire to secure by Letters Patent, is—

1. A system of supplying currents to electric railways, comprising normally-charged working-conductors extending along the line of way, a trunk-line shorter than and of greater current-carrying capacity than the working-conductors and extending from the source of current into the main field of distribution, and feeders connecting the working-conductor or conductors with the trunk at different points along its length.

2. A system of supplying currents to electric railways, comprising working-conductors extending along the line of way, a trunk-line comprising positive and negative conductors

both shorter than the working-conductors and extending from the source of current into the field of distribution, and feeders connecting the working-conductors with the trunk-line.

3. A system of supplying currents to electric railways, comprising the combination of a normally-charged sectional working conductor or conductors, a trunk-line shorter than and of greater current-carrying capacity than the working-conductors and extending from the source of current into the main field of distribution, and feeders connecting one side of the trunk-line with the separate insulated sections of working-conductor.

4. A system of supplying currents to electric railways, comprising an insulated sectional working-conductor of one polarity, a suitable return-conductor therefor, a trunk-line shorter than and of greater current-carrying capacity than the said working-conductor and connected at intervals thereto, the insulated side of the trunk-line being connected to the insulated working-conductor and its other side to the working-return.

5. In a system of supplying currents to electric railways, a sectional working conductor or conductors, a source of electricity remote therefrom, a trunk-feeder shorter than and of greater current-carrying capacity than the working-conductors and extending from the generator to the main field of distribution, feeders connecting the trunk with the several insulated sections, and means for equalizing the potential of the current supplied to all of the said separate sections near and remote of working-conductor.

6. In a system of supplying currents to electric railways, the combination of a sectional working conductor or conductors, a source of electricity remote therefrom, a trunk-line shorter than and of greater current-carrying capacity than the working-conductors and extending from the generator to the main field of distribution, feeders connecting the trunk with the several insulated sections, and means for equalizing the potential of the currents delivered through the trunk and feeders to the said separate sections of working-conductor comprising adjustable resistances placed in a plurality of the feeder-circuits.

7. In a system of supplying currents to electric railways, the combination of a sectional working-conductor, a source of electricity remote therefrom, a trunk-feeder extending from the generator to the main field of distribution, feeders connecting the trunk with the several insulated sections, an adjustable resistance in each feeder-circuit, and a safety device also included in each feeder-circuit.

8. In a system of supplying currents to electric railways, the combination of main working-conductors divided into separate insulated sections, a trunk-feeder shorter than and of greater current-carrying capacity than the line of working-conductors, branches sup-

- plying current separately thereto from the trunk-line, and an automatic current-regulator included between each feeder and its section of the working-conductor.
5. 9. In a system of supplying currents to electric railways, the combination of main working-conductors divided into separate insulated sections, circuits shorter than said working-conductors as a whole and supplying currents separately thereto from a suitable source, and an automatic current-regulator between each feeder and its section of the working-conductor, comprising a rheostat, a movable contact for switching in or cutting out more or less of the coils of the rheostat, connections between the movable contact and the feeder, a solenoid in circuit between the working-conductor and rheostat, a plunger for said solenoid, and connections between the core of the solenoid and the movable contact, whereby more or less of the resistance is placed in or withdrawn from the feeder-circuit.
10. In a system of supplying currents to electric railways, the combination, with a sectional working-conductor and feeders for each section thereof, of a fuse-box for each feeder-circuit, said fuse-box comprising a fusible strip between fixed terminals and a movable signal device normally sustained within the box by a fragile connection arranged in proximity to the fusible strip, whereby when the fuse is blown the signal will be released.
- 25 11. In a system of supplying currents to electric railways, the combination of a sectional working-conductor, a trunk-line shorter than and of greater current-carrying capacity than the working-conductor, feeders extending from the trunk to each section thereof, a fuse-box for each feeder-circuit, said fuse-box comprising a fusible strip between fixed terminals, and a movable signal device normally sustained within the box by a fragile connection arranged in proximity to the fusible strip, whereby when the fuse is blown the signal will be released.
- 30 12. A fuse-box comprising a fusible strip normally forming a part of the supply-circuit, a manual switch for opening said circuit when replacing a blown fuse, and a sig-

naling device hinged or pivoted within the fuse-box above an opening therein and normally sustained inside the box by a fragile connection secured or connected to the fuse and adapted to be destroyed when the fuse is blown, and thereby to liberate the signal, allowing the same to move downward through the opening in the box into sight.

13. In a system of supplying current to electric railways, a sectional working-conductor and means for connecting and insulating the ends of the sections thereof, comprising a section of insulating material, ears or bails secured to the extremity thereof and formed with grooves along their under edges and with upwardly-extending openings therein adjacent to the ends of the insulating-link, and conductors permanently secured in the grooves in the ears and having their ends passed upwardly and secured in the openings therein.

14. The combination, with the terminals of working-conductors, of an insulating section, metallic ears secured to each end thereof and formed with grooves along their under sides to receive the said conductors, and also formed with upwardly-extending openings adjacent to their point of attachment to the insulating section, and conductors secured within the grooves of the ears and having their ends passed upwardly through the openings therein.

15. In a system of supplying currents to electric railways, the combination, with normally-charged sectional main working-conductors and a continuous return-conductor arranged for multiple-arc distribution, of feeder-circuits extending between the source of current and each insulated section of the working-conductor, a main return-conductor, and a plurality of connections between said main return-conductor and the return working-conductor.

In testimony whereof I affix my signature in presence of two witnesses.

CHARLES J. VAN DEPOELE.
